UNITED STATES PATENT OFFICE.

CLARENCE EDMUND SKERRY, OF BRATTLEBORO, VERMONT, ASSIGNOR TO NATIONAL AUTOMATIC MACHINE COMPANY, OF BRATTLEBORO, VERMONT, A CORPORATION OF VERMONT.

STAMP-AFFIXING MACHINE.

1,314,760.

Specification of Letters Patent.

Patented Sept. 2, 1919.

Application filed July 12, 1916. Serial No. 108,810.

To all whom it may concern:

Be it known that I, CLARENCE E. SKERRY, a citizen of the United States, and resident of the city of Brattleboro, in the county of Windham and State of Vermont, have invented certain new and useful Improvements in Stamp-Affixing Machines, of which the following is a specification.

This invention relates to improvements in power operated mechanism for affixing postage stamps to envelopes or the like, and refers more particularly to machines of this character which perform all of the operations automatically after the envelop is started through the machine.

The object of this invention is to provide means for automatically discontinuing the feeding action upon the envelop during the time the stamp is being applied thereto.

With these and other objects in view, the invention consists of certain novel features of construction, as will be more fully described, and particularly pointed out in the appended claims.

In the accompanying drawings:

Figure 1— is a sectional elevation of the machine on line 1—1 of Fig. 3 showing the feed rolls in full and the mechanism by which they are separated during the time the stamp is being fixed to the envelop.

Fig. 2— is a view partly in section on line 2—2 of Fig. 1 showing the longitudinally movable cams which act upon and raise the feed roll.

Fig. 3— is a detail sectional view illustrating the operating cam in the affixing machine as about to act upon the lever arm and operate the rock shaft.

Referring to the drawings, 10 designates the table over which the envelopes to be stamped are fed by means of the feed rolls 11 and 12. The lower feed roll 11 is mounted on and driven through the shaft 13, by means not shown, said shaft being supported in the bearings 14 below the table, its upper edge extending through an opening 15 therein just above the upper surface thereof.

The upper feed roll 12 is mounted on the shaft 16 which is journaled in the end bearings 17. These bearings are each provided with a supporting stem 18 mounted to slide vertically through their respective bearings 19, which bearings are connected to the frame 21 that is bolted at 22 to the side 23 of the

table 10. A roll 20 is pivotally mounted in the upper end of each of these stems 18. The upper surface of this frame is grooved longitudinally as at 24, and in this groove is slidably mounted a bar 25 having two inclined or wedge-shaped members 26 and 27 mounted thereon to serve as cams for acting through the rollers 20 to raise the feed roll 12 when the cam bar 25 is moved to the left, and to release the roll to return to normal under influence of springs 33 to press against the lower roll 11 when the cam bar is released and permitted to return under influence of its spring 40.

In order to affect this longitudinal movement of the cam bar 25 in time with the stamp affixing mechanism, I have fixed a cam C to the intermittently rotatable shaft S, which cam when it is caused to rotate engages the arm 28 mounted on the shaft 29 to rock said shaft and swing the long arm 30 mounted thereon to reciprocate the cam bar 25 to which its upper end 31 is connected by the link 32, see Fig. 2.

The operation of my improved stamp affixing machine is as follows:—The envelopes are placed in a pile at the entering end of the machine and are fed automatically and successively to the feed rolls 11 and 12 in the usual way.

The envelop after being engaged by these rolls is advanced until its forward edge strikes the stop pin 37 and during its forward passage, it engages the trip lever 34 which operates through the arm 35 and shaft 36 to trip and start the stamp affixing mechanism in the manner shown and described in Letters Patent 1194693, granted August 15, 1916, on a co-pending application.

This trip action starts the cam shaft S to rotate and make one complete revolution, which operation causes the cam C to act upon the arm 28, shaft 29, arm 30 and cam bar 25 to move the wedge-shaped cams 26 and 27 beneath the rolls 20 and raise the feed roll 12 from the surface of the envelop which immediately stops the feed of the same.

During the time that this roll is raised from the envelop, the stamp affixing plunger 38, see Fig. 3, descends, the knife 39 severs the stamp from its strip 30, and affixes it to the envelop, all of which affixing mecha-

nism is illustrated in Patent Number 1,170,949. After the stamp has been affixed the continued rotation of the shaft C withdraws the stop pin 37 and permits the arm 5 30 under influence of the spring 40 to return, withdraws the cams from the rolls 20 and allows the feed roll 12 to again press the surface of the envelop against the lower driving roll causing the same to be advanced to another set of feed rolls, not herein shown, to carry it to any point desired.

I have shown and described only one means of supporting the envelop feed roll but any means for discontinuing the feeding action of said rolls upon the envelop during the interval of affixing the stamp will fall within the spirit and scope of my invention.

I claim:

- 20 1. An improvement in stamp affixing machines comprising a trip mechanism, a pair of envelop feeding rollers, means controlled by said trip mechanism for periodically separating said rolls to interrupt the feeding action thereof after each envelop has advanced a pre-determined distance, and stamp affixing means controlled by the trip mechanism and operable to affix a stamp during the period of interrupted feeding action.
- 25 2. An improvement in stamp affixing machines comprising a trip mechanism, a pair of envelop feeding rolls, means moving one of said rolls away from the other, connections between the roll-moving means and

the trip mechanism to effect interruption of the feeding action of said rolls after each envelop has advanced a predetermined distance, and stamp affixing means controlled by the trip mechanism and operable to affix a stamp during the period of interrupted feeding action.

3. An improvement in stamp affixing machines comprising a trip mechanism, a pair of envelop feeding rolls, a suspended frame having means for supporting one of said rolls, a cam engaging said suspended frame, means controlled by the trip mechanism for operating the cam to move the frame in a direction to separate said rolls, and stamp affixing means controlled by the trip mechanism and operable to affix a stamp during the period of interrupted feeding action.

4. An improvement in stamp affixing machines comprising a trip mechanism, a pair of envelop feeding rollers, means controlled by said trip mechanism for periodically separating said rolls to interrupt the feeding action thereof after each envelop has advanced a pre-determined distance, and a stamp plunger controlled by the trip mechanism and operable during the period of operation of said rolls.

In testimony whereof I affix my signature in presence of two witnesses.

CLARENCE EDMUND SKERRY.
